(57) **ABSTRACT**

A plate joiner including a fence support, a drive, and a fence system. The fence support includes a cutter and a contact surface, which defines a cutter slot. The cutter is arranged and configured to protrude from fence support through cutter slot to make a plunge cut into a surface of a workpiece when the contact surface is pressed against the surface and the cutter is plunged into the workpiece by pushing on a rearward handle portion of the tool. The drive is arranged and configured to rotatably drive the cutter through a motor.

A preferred fence system includes an angle adjustment system arranged and configured to position the fence at a wide range of fence angles and, at any selected distance from a top face of the workpiece to the fence, the distance from the top face of the workpiece to the cutter remains constant as the front fence angle is adjusted. A preferred fence system includes a trunnion which pivotally couples the front fence to the fence system. A preferred fence system also includes an angle segment member, which has two slots used to position the fence in two ranges of fence angles.

PLATE JOINER FENCE ANGLE ADJUSTMENT SYSTEM

BACKGROUND AND SUMMARY OF THE INVENTION

The present invention relates to a plate joiner including a fence support, a drive, and a fence system. The fence support includes a cutter and a contact surface, which defines a cutter slot. The cutter is arranged and configured to protrude from fence support through cutter slot to make a plunge cut into a surface of a workpiece when the contact surface is pressed against the surface and the cutter is plunged into the workpiece by pushing on a rearward handle portion of the tool. The drive is arranged and configured to rotatably drive the cutter through a motor.

A preferred fence system includes an angle adjustment system arranged and configured to position the fence at a wide range of fence angles and, at any selected distance from a top face of the workpiece to the fence, the distance from the top face of the workpiece to the cutter remains constant as the front fence angle is adjusted. A preferred fence system includes a trunnion which pivotally couples the front fence to the fence system. A preferred fence system also includes an angle segment member, which has two slots used to position the fence in two ranges of fence angles.

BRIEF DESCRIPTION OF THE DRAWINGS

FIG. 1 illustrates a side elevational view of a preferred embodiment of the present plate joiner and fence system;

FIG. 2 illustrates a left side elevational view of the plate joiner and fence system shown in FIG. 1;

FIG. 3 shows a top plan view of the plate joiner and fence system shown in FIG. 1;

FIG. 4 shows a bottom plan view of the plate joiner and fence system shown in FIG. 1;

FIG. 5 shows a front elevational view of the plate joiner and fence system shown in FIG. 1;

FIG. 6 shows a back elevational view of the plate joiner and fence system shown in FIG. 1;

FIG. 7 shows a top left perspective view of the plate joiner and fence system shown in FIG. 1;

FIG. 8 shows a bottom right perspective view of the plate joiner and fence system shown in FIG. 1;

FIG. 9 shows a left elevational cross-sectional profile (taken along cutting line 8—8 of FIG. 6) illustrating the preferred plate joiner as well as a preferred fence system;

FIG. 10 illustrates a right elevational view of the fence system shown in FIG. 1;

FIG. 11 shows a left elevational view of the fence system shown in FIG. 10;

FIG. 12 shows a top plan view of the fence system shown in FIG. 10;

FIG. 13 shows a front elevational view of the fence system shown in FIG. 10;

FIG. 14 illustrates a bottom plan view of the fence system shown in FIG. 10, with a portion of the cutter cover base cut away;

FIG. 15 shows a rear elevational view of the fence system shown in FIG. 10;

FIG. 16 shows a top plan cross-sectional profile (taken along cutting line 14—14 of FIG. 15) illustrating a preferred fence system;

FIG. 17 shows a left side elevational cross-sectional profile (taken along cutting line 15—15 of FIG. 13) illustrating a preferred fence system;

FIG. 18 illustrates a back elevational cross-sectional profile (taken along cutting line 16—16 of FIG. 16) illustrating a preferred fence system including portions of the lower gear housing of the plate joiner;

FIGS. 19A—E show elevational and top and bottom plan views of the fence system of FIG. 10 with the front fence at an angle of zero degrees;

FIGS. 20A—E show elevational and top and bottom plan views of the fence of FIG. 10 with the front fence at an angle of 90 degrees in the first range of front fence angles;

FIGS. 21A—E show elevational and top and bottom plan views of the fence system of FIG. 10 with the front fence at an angle of 90 degrees with the height of the front fence raised compared to the position in FIG. 20;

FIGS. 22A—E show elevational and top and bottom plan views of the fence system of FIG. 10 with the front fence at an angle of 135 degrees;

FIG. 23 shows a bottom plan view of the fence system of FIG. 10 with the cutter cover base removed and the safety lever in a rearward release position;

FIG. 24 shows a bottom plan view of the fence system of FIG. 10 with the cutter cover base removed and with the safety lever in a forward release position;

FIGS. 25A and 25B show a top left perspective view and a bottom right perspective view of the front fence, of the fence system of in FIG. 10, illustrating and the groove member of the trunnion;

FIGS. 26A and 26B show a bottom left perspective view and a top right perspective view and a top right perspective view, respectively, of the rear fence, of the fence system of in FIG. 10;

FIGS. 27A—D show perspective views of the trunnion member illustrating the ridge member;

FIG. 28A shows a front view of an embodiment of a fence system including a quick release screw;

FIG. 28B illustrates a top view of an embodiment of the fence system including a quick release screw;

FIG. 28C is a left-side elevational cross-sectional profile taken along cutting line 28—28 of FIG. 28A illustrating the quick release screw.

DETAILED DESCRIPTION OF THE PREFERRED EMBODIMENT

A plate joiner makes a plunge cut in a joint surface of a piece of wood which allows the piece of wood to be joined to another piece of wood having an oppositely disposed groove. A biscuit (a thin plate of wood or other material) and glue are placed in the grooves, and the pieces of wood are joined to provide an accurate and strong joint. A plate joiner generally includes a housing, a drive unit, and a rotating cutter. A portion of the housing contacts a joint surface and, as a portion of the housing is pushed forward, the rotating cutter moves forward, engages the joint surface at the desired location, and cuts into the joint surface. Releasing forward pressure on the housing then retracts the cutter. Thus, a plate joiner provides an easy method of producing a strong and aesthetic joint in wood.

The cutter is driven by a drive including a motor located within the housing, and a gear system driven by the motor and located in a forward gear housing portion of the housing. The gear system includes a motor driven shaft rotatably driven by the motor, a generally right angle coupling of the motor driven shaft, using beveled gear, to a cutter shaft that rotatably drives the cutter. The rotating cutter is configured to cut into the joint surface.

The preferred plate joiner tool can be configured into many highly versatile configurations. The plate joiner system is arranged and configured with a fence that can be positioned in a wide range of fence angles and, at any selected distance from a top face of the workpiece to the fence, the distance from the top face of the workpiece to the cutter remains constant as the front fence angle is adjusted. The plate joiner is configured for substantially continuous adjustment of fence height while restraining lateral and tortional movement of the fence and providing an accurate measure of the height of the fence from any point in the thickness of the blade. The plate joiner system is also arranged and configured to provide a plurality of release positions that reduce the distance traveled in making a plunge cut for a smaller blade and to prevent a blade from protruding from the tool in a release position. Such versatility is found in no other plate joiner system.

To accomplish this, the present plate joiner system preferably includes a fence system including an angle adjustment system having a trunnion and an angle segment member. The angle segment member includes two slots used to position the fence in two ranges of fence angles. The plate joiner system, preferably, also includes a height adjustment system including an adjustment screw arranged and configured to provide substantially continuous adjustment of fence height and guide pins which restrain lateral and tortional movement of the fence at the height it is adjusted and locked. A preferred plate joiner system also includes a cutter plunge system 86 arranged and configured for sliding the cutter from one of a plurality of release positions to a plunge position. A preferred plate joiner includes a cutter inside a removable cutter base cover.

The preferred plate joiner system includes a fence support 14, a drive 170, and a fence system 129 (see FIG. 9). Preferred fence support 14 includes a cutter 113 and a contact surface 24, which defines a cutter slot 38. Cutter 113 is arranged and configured to protrude from fence support 14 through cutter slot 38 to make a plunge cut into a surface of a workpiece when contact surface 24 of fence support 14 is pressed against the surface and cutter 113 is plunged into the workpiece by pushing on a rearward handle portion 172 of the tool. Drive 170 is arranged and configured to rotatably drive cutter 113 through a motor which may be an electrical motor operated live or battery power, or which may be an air motor. In a preferred configuration, contact surface 24 includes abrasive, which provides stability of the surface against the work piece. For example, the grit of the abrasive contacts the workpiece and prevents motion of the tool relative to the workpiece.

A preferred fence system 129 includes a front fence 12 and an angle adjustment system 39, which is arranged and configured for adjusting an angle of front fence 12. Using this preferred fence system 129, at any selected distance from a top face of the workpiece to the front fence 12, the distance from the top face of the workpiece to cutter 113 remains constant as the angle of front fence 12 is adjusted. The preferred mechanism for accomplishing this is described further below.

Front fence 12 includes a planar face 40, which, at a fence angle of 0°, is coplanar with contact surface 24. At fence angles greater than 0°, planar face 40 of front fence 12 defines a plane that intersects with the plane of contact surface 24. The distance from this intersection to any particular part of cutter 113 is the distance from a top face of the workpiece to any particular part of cutter 113. As shown in FIG. 13, front fence 12 includes cut away portions so that from the front of the plate joiner, front fence 12 has

a shape resembling a squared-off letter "A". The cut away portions of front fence 12 reduce the weight of the fence and, optionally, accommodate protruding portions of gear housing 125 when making a plunge cut.

Front fence 12 pivots with respect to fence support 14 and cutter 113 by employing angle adjustment system 39. Angle adjustment system 39 and front fence 12 define an axis on which front fence 12 pivots. When this pivot axis is not in the plane of contact surface 24, that is, when this pivot axis is in front of or behind the contact surface, the distance from the top face of the workpiece to any particular part of cutter 113 changes as the front fence angle is varied. Advantageously, angle adjustment system 39 and front fence 12 are arranged and configured to provide a pivot axis substantially in a plane defined by contact surface 24. This orientation of the pivot axis is a way to achieve a fence system in which, at any selected distance from a top face of the workpiece to any particular part of cutter 113, the distance from the top face of the workpiece to the particular part of cutter 113 remains constant as a front fence angle is adjusted.

Advantageously, angle adjustment system 39 employs a trunnion 41 to pivot front fence 12 on a pivot axis in a plane defined by contact surface 24. A trunnion typically includes a cup shaped receptacle which supports a rod or disk on which a device swivels. For example, the two opposite gudgeons on which a cannon swivels or pivots vertically form a trunnion. In this respect, a trunnion is particularly useful for providing a consistent vertical pivot motion without substantial lateral play.

Trunnion 41, in which a generally semicircular cup 42 receives a generally semicircular disk 43, is a mechanism that provides a pivot axis that is in the plane of contact surface 24. Cup 42 is defined by an arcuate ridge member 44. Disk 43, is a portion of groove member 45, which defines an arcuate groove 46 around disk 43. Arcuate groove 46 pivotally engages ridge member 44 in a manner such that disk 43 is retained in cup 42. Preferably, front fence 12 includes groove member 45 and rear fence 13 includes ridge member 44.

In the embodiment shown in the Figures, rear fence 13 includes a rear fence member 47 and a trunnion member 48, which includes groove member 45. Generally, ridge member 44 can be a component of either front fence 12 or rear fence 13, groove member 45 can be a component of whichever of front fence 12 or rear fence 13 does not include ridge member 44, and trunnion member 48 can include either ridge member 44 or groove member 45.

In the embodiment shown in the Figures, trunnion 41, includes left side trunnion pivot member 31 including ridge member 44 and groove member 45, and a right side trunnion pivot member 32 including ridge member 44 and a groove member 45. Generally trunnion 41 will include two trunnion pivot members, although a single member can include the features of both right side and left side trunnion pivot members.

Trunnion 41 can be arranged and configured to provide a pivot axis in a plane defined by contact surface 24, in a plane defined by planar surface 40 of front fence 12, in both of these planes, or in neither of these planes.

A preferred embodiment of the plate joiner system includes, as part of the system for adjusting the fence angle, an angle segment member 15 arranged and configured to position front fence 12 at a selected angle between a plane defined by planar surface 40 of front fence 12 and a plane defined by contact surface 24. Angle segment member 15

defines first slot 49 and second slot 50, which are arranged and configured to position the fence in a first and second range of fence angles, respectively.

FIG. 10 illustrates a preferred embodiment of angle segment member 15. In this embodiment, angle segment member includes a plate 51 pivotally coupled to front fence 12 and configured to define slots 49 and 50. First slot 49 and second slot 50 are each configured as an arcuate slot and are connected by third slot 52. In the embodiment shown in FIG. 10, the first range of fence angles is about 0° to about 90°, and the second range of fence angles is about 90° to about 135°. First angle scale 29 and second angle scale 30 are generally parallel to the corresponding slots and include numerical indicia 76 arranged and configured to indicate the angle of front fence 12. Slots 49 and 50 are arranged and configured to provide approximately evenly spaced indicia 76 for a given change in fence angles. FIG. 10 illustrates approximately evenly spaced indicia 76 for each 10° change in fence angle.

First angle scale 29 and second angle scale 30 are each associated with an angle indicator, first angle indicator 54 and second angle indicator 55, respectively. When front fence 12 is positioned in the first range of fence angles, first angle indicator 54 is generally adjacent to first angle scale 29 and indicates the fence angle on first angle scale 29. When front fence 12 is positioned in the second range of fence angles, second indicator 55 is generally adjacent to second angle scale 30 and indicates the fence angle on second angle scale 30.

Advantageously, first angle indicator 54 is not adjacent to first angle scale 29 when front fence 12 is positioned in the second range of fence angles. That is, angle segment 15 moves so that first angle indicator 54 is dissociated from first angle scale 29 when front fence 12 is positioned in the second range of fence angles (see FIG. 22). Similarly, second angle indicator 55 is not adjacent to second angle scale 30 when front fence 12 is positioned in the first range of fence angles. That is, angle segment 15 moves so that second angle indicator 55 is dissociated from second angle scale 30 when front fence 12 is positioned in the first range of fence angles (see FIG. 10).

In another preferred embodiment, angle adjustment system 39 is arranged and configured to provide a positive stop at one or more fence angles. For example, angle segment member 15 can include a stop member, such as tab 56, that contacts another portion of the fence system to provide a positive stop. Such a positive stop can be adjustable if either tab 56 or the part contacted by tab 56 includes a stop adjustment mechanism, such as an adjustable set screw.

FIGS. 12 and 14 show stop member 56 configured to provide a positive stop at 90°. Using first slot 49 to position front fence 12 at 90° brings stop member 56 into contact with rear fence 13 providing a positive stop. Optionally, rear fence 13 can include an adjustable set screw (not shown) at the point at which stop member 56 contacts rear fence 13 to provide an adjustable positive stop. It is advantageous to provide an adjustable stop at 90° so that plunge cuts can be adjusted to be made accurately at substantially 90°. An analogous arrangement of stop member 56 and contact point on rear fence 13 can provide a positive stop at 135° (not shown). A positive stop at 0° is provided by contact between rear fence 13 and a contact point 78 on the rearward surface of front fence 12.

Front fence 12 can be retained at a desired fence angle. Angle adjustment system 39 includes an angle locking system 57. Angle locking system 57 includes angle locking

knob 3 that is arranged and configured to bias against angle segment member 15. Angle locking knob 3 is threadably engaged on a pin (not shown) that slidably engages slots 49 and 50 in angle segment member 15. Knob 3 when tightened on the threaded pin biases angle segment member 15 against rear fence 13.

The preferred plate joiner system includes a height adjustment system 58, which is a subsystem of fence system 129. Height adjustment system 58 is preferably arranged and configured to adjust the distance from the top face of a workpiece to the cutter in a substantially continuous manner and with torsional and lateral stability. Optionally, height adjustment system 58 can provide a combination of rapid, discontinuous height adjustment to approximately the desired fence height, and substantially continuous adjustment to achieve the desired fence height.

Height adjustment system 58 achieves substantially continuous adjustment of fence height using a threaded rod 59. Threaded rod 59 is supported by and rotatably retained by a vertical member 60 portion of fence support 14 and threadably engages rear fence 13. Vertical member 60 and rear fence 13 are both substantially perpendicular to cutter 113. Threaded rod 59 does not move vertically relative to vertical member 60, and as threaded rod 59 is rotated, rear fence 16 moves up and down relative to vertical member 60 and cutter 113. Since front fence 12 is pivotally attached to rear fence 13, front fence 12 also moves vertically with rear fence 13 and relative to cutter 113.

Threadable engagement of rear fence 13 with threaded rod 59 results in substantially continuous vertical adjustment of the fence. Small increments of rotation allow small increments of vertical movement on the incline of the threads. In a preferred embodiment, by knowing the pitch of the thread, each revolution or partial revolution provides a predetermined height adjustment optionally, using a quick release screw 80 rear fence 13 can disengage from the threads of threaded rod 59, for rapid, discontinuous height adjustment. When the approximate fence height is achieved by discontinuous adjustment, rear fence 13 can reengage the threads of threaded rod 59 for continuous adjustment to the desired fence height.

Height adjustment is achieved with torsional and lateral stability by using first guide rod 61 and second guide rod 18 to guide vertical adjustment of rear fence 13. As shown in the Figures, first guide rod 61 and second guide rod 18 are components of fence support 14. Guide rod frames 62 and 63 are components of rear fence 13. In this way, guide rods 18 and 61 are retained by fence support 14 vertical member 60, and cannot move vertically relative to vertical member 60. Yet, guide rods 18 and 61 slidably engage rear fence 13, so that rear fence 13 can slide vertically relative to the guide rods for height adjustment.

As shown in FIG. 16 first guide rod 61 is positioned by first guide rod frame 62 and second guide rod 18 is positioned by second guide rod frame 63. Each guide rod frame defines a space around the corresponding guide rod. Preferably, first guide rod frame 62 comprises first through hole 64 in rear fence 13 and second guide rod frame 63 comprises second through hole 65 in rear fence 13. The space between first guide rod 61 and first guide rod frame 62 is advantageously narrower than the space between second guide rod 18 and second guide rod frame 63. Preferably, first through hole 64 has a substantially smaller diameter than second through hole 65, which results in a narrow space between first guide rod 61 and first guide rod frame 62 than between second guide rod 18 and second guide rod frame

63. First guide rod **61** and second guide rod **62** are advantageously of substantially equal diameter. The combination of a tight tolerance for first guide rod **61** and a looser tolerance for second guide rod **18** is one manner in which lateral and torsional movement of rear fence **13** is restrained, while maintaining manufacturing economies.

Height adjustment system **58** includes a height locking system **82** for securing front fence **12** at the desired height and for providing reproducible lateral and torsional positioning and stability of front fence **12** at different heights. Height locking system **82** includes height locking knob **84**, threaded pin **66** and plug **19**. Height locking system **82** is arranged and configured to bias against a second guide rod **18** and to bias first guide rod **61** against first guide rod frame **62**. Individual components of height locking system **82** are configured to bring this about. Turning knob **84** threadably advances threaded pin **66** into rear fence **13** which biases plug **67** against guide rod **18**. As this biasing continues rear fence **13** is moved laterally through a distance less than the space surrounding first guide pin **61**, and first guide pin **61** is biased against guide rod frame **62**. Biasing guide rod **61** against guide rod frame **62** provides reproducible and stable lateral and torsional positioning of rear fence **13**, and front fence **12**.

The preferred fence system also includes a height gauge **68**, which is arranged and configured to provide a reading of fence height relative to any point on the thickness of cutter **113**, which corresponds to any point in the thickness of the slot cut by cutter **113**. In an especially preferred embodiment, height gauge **68** provides an accurate reading of fence height at any fence angle.

Height gauge **68** includes a scale **10** and a height indicator **69**. As shown in the figures, height scale **10** is arranged on a surface of fence support **14** vertical member **60**, and height indicator **69** is on rear fence **13** generally adjacent to vertical member **60**. Height indicator **69** includes a visible indicator **70** with a thickness along the height scale **10** substantially equivalent to the thickness of the cutter that indicates fence height using height scale **10**. In one preferred embodiment, visible indicator **70** is in the shape of a raised rectangle.

As a consequence of this arrangement, by visualizing measurement along the thickness of the visible indicator **70**, height gauge **68** indicates the distance from a face of the workpiece to any point in the thickness of cutter **113**. With this arrangement of the height gauge and a preferred embodiment of the angle adjustment system, in which at any selected distance from a top face of the workpiece to the fence, the distance from the top face of the workpiece to the cutter remains constant as the front fence angle is adjusted, the height gauge is accurate each selected front fence angle.

In making a plunge cut with the plate joiner, cutter **113** starts in a release position and, as contact surface **24** is pressed against the workpiece, by pushing on a rearward handle portion of the tool, cutter **113** moves forward to a plunge position while cutting a slot in the workpiece. Preferably, in a release position, cutter **113** is completely within fence support **13**, which includes cutter housing cover **16**, and cutter housing base **17**. If such a plate joiner has only a single release position and can use different sized blades, a smaller blade must travel a greater distance before it contacts the workpiece, which is an inconvenience for the plate joiner operator. Preferred cutter sizes include diameters of about 4 inches and about 2 inches. A more convenient arrangement provides a plurality of release positions to reduce the distance from release position to plunge position for smaller blades.

A preferred embodiment of the plate joiner system includes a cutter plunge system **86** arranged and configured for sliding cutter **113** from one of a plurality of release positions to a plunge position. The release positions are configured to reduce the distance between the release and plunge positions as cutter size is reduced. Preferably the distance from the forward edge of the blade in the release position to the contact surface is approximately constant for different sized blades in different release positions. Cutter plunge system **86** includes safety lever system **71**, which is arranged and configured to position the cutter at one or more release positions. Safety lever system **71** includes pivot pin **28**, which can be a rivet, safety lever **25**, and guide pin **26**. Safety lever **25** pivots on pivot pin **28** and guide pin **26** engages an aperture **72** in blade housing cover **16** and stoppably engages lower gear housing **73** to retain the cutter in the release position.

The plurality of release positions configures the plate joiner system to advantageously house cutters of two or more different sizes. For example, a four inch cutter is advantageous for general use, and a smaller, two inch, cutter is advantageous for applications such as joining face frames. The preferred plate joiner system can house either a two inch blade or a four inch blade, and the cutter plunge system **86** provides for reduced travel of the two inch cutter.

In the release position providing reduced travel for a smaller blade, safety lever **25** prevents installing a larger blade, preferably by physically blocking installation of the larger blade. In such a manner, a safety lever prevents installing a large blade in a release position in which it would protrude from the cutter slot in the release position. The larger blade is accommodated at a more rearward release position.

In a forward position, safety lever **25** is configured to direct cutting dust toward dust aperture **74**. The slightly arcuate shape of safety lever **25** provides smooth circulation of air and dust when safety lever **25** is in a rearward release position, and aids in directing dust towards aperture **74** when safety lever **25** is in a forward release position.

The above specification, examples and data provide a complete description of the manufacture and use of the composition of the invention. Since many embodiments of the invention can be made without departing from the spirit and scope of the invention, the invention resides in the claims hereinafter appended.

We claim:

1. A plate joiner, comprising:

- a. a fence support comprising a contact surface, a cutter slot defined by the contact surface, and a cutter; the cutter being arranged and configured to protrude from the fence support through the cutter slot and to make a plunge cut into a surface of a workpiece when the contact surface of the fence support is pressed against the surface and the cutter is plunged into the workpiece;
- b. a drive arranged and configured to rotatably drive the cutter; and
- c. a fence system comprising a front fence, an angle adjustment system, and a pivot axis defined by the front fence and the angle adjustment system; the pivot axis being substantially in a plane defined by the contact surface; the angle adjustment system being arranged and configured for adjusting a front fence angle.

2. The plate joiner of claim 1, wherein at any selected distance from a top face of the workpiece to the cutter, the distance from the top face of the workpiece to the cutter remains constant as the front fence angle is adjusted.

3. The plate joiner of claim 1, wherein the fence system further comprises two trunnions and a rear fence, which is substantially perpendicular to the cutter; the front fence and rear fence being pivotally coupled by the trunnions.

4. The plate joiner of claim 3, wherein the trunnion comprises an arcuate ridge member and a groove member defining an arcuate groove, the ridge member pivotally engaging the groove member; the front fence comprising the ridge member and the rear fence comprising the groove member, or the front fence comprising the groove member and the rear fence comprising the ridge member. 10

5. The plate joiner of claim 4, wherein the front fence comprises the groove member and the rear fence comprises the ridge member.

6. The plate joiner of claim 4, wherein the rear fence 15 comprises a rear fence member and a trunnion member, the trunnion member being coupled to the rear fence member and comprising the groove member or the ridge member.

7. The plate joiner of claim 1, wherein the angle adjustment system comprises an angle segment member arranged 20 and configured to position the front fence at a selected angle between a plane defined by the front fence and a plane defined by the contact surface; and the angle segment member defines a first slot and a second slot; the first slot being arranged and configured to position a first range of front fence angles; the second slot being arranged and 25 configured to position a second range of front fence angles.

8. The plate joiner of claim 7, wherein the angle segment member is pivotally coupled to the front fence and slidably engages the rear fence.

9. The plate joiner of claim 7, wherein the first slot comprises an arcuate slot and the second slot comprises an arcuate slot.

10. The plate joiner of claim 7, wherein the angle adjustment system is arranged and configured to position the front fence in the first range of angles comprising about 0° to about 90° and the second range of angles comprising about 90° to about 135°. 35

11. The plate joiner of claim 7, wherein the angle adjustment system defines a third slot arranged and configured to 40 connect the first and second slots.

12. The plate joiner of claim 7, wherein the angle adjustment system is arranged and configured to provide a positive stop at one or more front fence angles.

13. The plate joiner of claim 12, wherein the angle 45 segment member comprises a stop member arranged and configured to stoppably contact the rear fence to provide a positive stop.

14. The plate joiner of claim 13, wherein the angle segment member and rear fence are arranged and configured 50 to provide an adjustable stop.

15. The plate joiner of claim 14, wherein the rear fence comprises a set screw arranged and configured to stoppably contact the stop member.

16. The plate joiner of claim 15, wherein the positive stop 55 is at a front fence angle of about 90° or about 135°.

17. The plate joiner of claim 12, wherein the front fence is arranged and configured to stoppably contact the rear fence to provide a positive stop.

18. The plate joiner of claim 17, wherein the positive stop 60 is at a front fence angle of about 0°.

19. The plate joiner of claim 12, wherein the angle adjustment system is arranged and configured to provide a positive stop at a front fence angle of about 0°, about 90° or about 135°.

20. The plate joiner of claim 7, wherein the angle adjustment system comprises an angle locking system arranged

and configured to retain the front fence at a desired angle; the angle locking system comprising a pin arranged and configured to alternatively slidably engage the first arcuate slot and the second arcuate slot and a locking knob biasing the angle segment member against the rear fence.

21. The plate joiner of claim 1, wherein:

a. the fence system further comprises a height adjustment system, and a height gauge; the height adjustment system being arranged and configured for adjusting fence height;

b. the height gauge comprises a scale and a height indicator; the scale being arranged and configured to provide a measurement of front fence height; the height indicator comprising a visible indicator with a thickness along the scale substantially equivalent to the thickness of the cutter; the height indicator being arranged and configured to indicate a front fence height on the height scale;

c. whereby by visualizing the measurement along the thickness of the visible indicator, the height gauge indicates the distance from a face of the workpiece to any point in the thickness of the cutter.

22. The plate joiner of claim 21, wherein the fence support further comprises a vertical member, and the height adjustment system further comprises the vertical member and a rear fence; the height scale is adjacent to the rear fence; and the rear fence comprises the visible indicator.

23. The plate coiner of claim 21, wherein the visible indicator comprises a raised rectangle.

24. The plate joiner of claim 21, wherein the height gauge is accurate at each selected front fence angle.

25. A plate joiner, comprising:

a. a fence support comprising a contact surface, a cutter slot defined by the contact surface, and a cutter; the cutter being arranged and configured to protrude from the fence support through the cutter slot and to make a plunge cut into a surface of a workpiece when the contact surface of the fence support is pressed against the surface and the cutter is plunged into the workpiece;

b. a drive arranged and configured to rotatably drive the cutter; and

c. a fence system comprising a front fence, an angle adjustment system, and a pivot axis defined by the front fence and the angle adjustment system; the pivot axis being substantially in a plane defined by the contact surface; the angle adjustment system being arranged and configured for adjusting a front fence angle;

d. whereby, at any selected distance from a top face of the workpiece to the fence, the distance from the top face of the workpiece to the cutter remains constant as the front fence angle is adjusted.

26. The plate joiner of claim 25, wherein the fence system further comprises two trunnions and a rear fence, which is substantially perpendicular to the cutter; the front fence and rear fence being pivotally coupled by the trunnions.

27. The plate joiner of claim 26, wherein the trunnion comprises an arcuate ridge member and a groove member defining an arcuate groove, the ridge member pivotally engaging the groove member; the front fence comprising the ridge member and the rear fence comprising the groove member, or the front fence comprising the groove member and the rear fence comprising the ridge member.

28. The plate joiner of claim 27, wherein the front fence comprises the groove member and the rear fence comprises the ridge member.

29. The plate joiner of claim 27, wherein the rear fence comprises a rear fence member and a trunnion member, the

trunnion member being coupled to the rear fence member and comprising the groove member or the ridge member.

30. The plate joiner of claim 25, wherein the angle adjustment system comprises an angle segment member arranged and configured to position the front fence at a selected angle between a plane defined by the front fence and a plane defined by the contact surface; and the angle segment member defines a first slot and a second slot; the first slot being arranged and configured to position a first range of front fence angles; the second slot being arranged and configured to position a second range of front fence angles. 5

31. The plate joiner of claim 30, wherein the angle segment member is pivotally coupled to the front fence and slidably engages the rear fence.

32. The plate joiner of claim 30, wherein the first slot comprises an arcuate slot and the second slot comprises an arcuate slot. 10

33. The plate joiner of claim 30, wherein the angle adjustment system is arranged and configured to position the front fence in the first range of angles comprising about 0° to about 90° and the second range of angles comprising about 90° to about 135°. 20

34. The plate joiner of claim 30, wherein the angle adjustment system defines a third slot arranged and configured to connect the first and second slots. 25

35. The plate joiner of claim 30, wherein the angle adjustment system is arranged and configured to provide a positive stop at one or more front fence angles.

36. The plate joiner of claim 35, wherein the angle segment member comprises a stop member arranged and configured to stoppably contact the rear fence to provide a positive stop. 30

37. The plate joiner of claim 36, wherein the angle segment member and rear fence are arranged and configured to provide an adjustable stop contact.

38. The plate joiner of claim 37, wherein the rear fence comprises a set screw arranged and configured to stoppably contact the stop member.

39. The plate joiner of claim 38, wherein the positive stop is at a front fence angle of about 90° or about 135°.

40. The plate joiner of claim 35, wherein the front fence comprises a stop member arranged and configured to stoppably contact the rear fence to provide a positive stop.

41. The plate joiner of claim 40, wherein the positive stop is at a front fence angle of about 0°.

42. The plate joiner of claim 35, wherein the angle adjustment system is arranged and configured to provide a positive stop at a front fence angle of about 0°, about 90° or about 135°.

43. The plate joiner of claim 30, wherein the angle adjustment system comprises an angle locking system arranged and configured to retain the front fence at a desired angle; the angle locking system comprising a pin arranged and configured to alternatively slidably engage the first arcuate slot and the second arcuate slot and a locking nut biasing the angle segment member against the rear fence. 55

44. The plate joiner of claim 25, wherein:

a. the fence system further comprises a height adjustment system, and a height gauge; the height adjustment system being arranged and configured for adjusting fence height;

b. the height gauge comprises a scale and a height indicator; the scale being arranged and configured to provide a measurement of front fence height; the height indicator comprising a visible indicator with a thickness along the scale substantially equivalent to the

thickness of the cutter; the height indicator being arranged and configured to indicate a front fence height on the height scale;

c. whereby by visualizing the measurement along the thickness of the visible indicator, the height gauge indicates the distance from a face of the workpiece to any point in the thickness of the cutter.

45. The plate joiner of claim 44, wherein the fence support further comprises a vertical member, and the height adjustment system further comprises the vertical member and a rear fence; the height scale is adjacent to the rear fence; and the rear fence comprises the visible indicator. 10

46. The plate joiner of claim 44, wherein the visible indicator comprises a raised rectangle.

47. The plate joiner of claim 44, wherein the height gauge is accurate at each selected front fence angle. 15

48. A plate joiner, comprising:

a. a fence support comprising a contact surface, a cutter slot defined by the contact surface, and a cutter; the cutter being arranged and configured to protrude from the fence support through the cutter slot and to make a plunge cut into a surface of a workpiece when the contact surface of the fence support is pressed against the surface and the cutter is plunged into the workpiece;

b. a drive arranged and configured to rotatably drive the cutter; and

c. a fence system comprising a front fence, and an angle adjustment system; the angle adjustment system comprising means for adjusting a front fence angle to provide, at any selected distance from a top face of the workpiece to the fence, that the distance from the top face of the workpiece to the cutter remains constant as the front fence angle is adjusted.

49. The plate joiner of claim 48, wherein the fence system further comprises a pivot axis defined by the front fence and the angle adjustment system; the pivot axis being substantially in a plane defined by the contact surface. 35

50. The plate joiner of claim 48, wherein the fence system further comprises two trunnions and a rear fence, which is substantially perpendicular to the cutter; the front fence and rear fence being pivotally coupled by the trunnions.

51. The plate joiner of claim 50, wherein the trunnion comprises an arcuate ridge member and a groove member defining an arcuate groove, the ridge member pivotally engaging the groove member; the front fence comprising the ridge member and the rear fence comprising the groove member, or the front fence comprising the groove member and the rear fence comprising the ridge member. 45

52. The plate joiner of claim 51, wherein the front fence comprises the groove member and the rear fence comprises the ridge member.

53. The plate joiner of claim 51, wherein the rear fence comprises a rear fence member and a trunnion member, the trunnion member being coupled to the rear fence member and comprising the groove member or the ridge member. 55

54. The plate joiner of claim 48, wherein the angle adjustment system comprises an angle segment member arranged and configured to position the front fence at a selected angle between a plane defined by the front fence and a plane defined by the contact surface; and the angle segment member defines a first slot and a second slot; the first slot being arranged and configured to position a first range of front fence angles; the second slot being arranged and configured to position a second range of front fence angles.

55. The plate joiner of claim 54, wherein the angle segment member is pivotally coupled to the front fence and slidably engages the rear fence. 65

56. The plate joiner of claim 54, wherein the first slot comprises an arcuate slot and the second slot comprises an arcuate slot.

57. The plate joiner of claim 54, wherein the angle adjustment system is arranged and configured to position the front fence in the first range of angles comprising about 0° to about 90° and the second range of angles comprising about 90° to about 135°.

58. The plate joiner of claim 54, wherein the angle adjustment system defines a third slot arranged and configured to connect the first and second slots.

59. The plate joiner of claim 54, wherein the angle adjustment system is arranged and configured to provide a positive stop at one or more front fence angles.

60. The plate joiner of claim 59, wherein the angle segment member comprises a stop member arranged and configured to stoppably contact the rear fence to provide a positive stop.

61. The plate joiner of claim 60, wherein the angle segment member and rear fence are arranged and configured to provide an adjustable stop contact.

62. The plate joiner of claim 61, wherein the rear fence comprises a set screw arranged and configured to stoppably contact the stop member.

63. The plate joiner of claim 62, wherein the positive stop is at a front fence angle of about 90° or about 135°.

64. The plate joiner of claim 59, wherein the front fence comprises a stop member arranged and configured to stoppably contact the rear fence to provide a positive stop.

65. The plate joiner of claim 64, wherein the positive stop is at a front fence angle of about 0°.

66. The plate joiner of claim 59, wherein the angle adjustment system is arranged and configured to provide a positive stop at a front fence angle of about 0°, about 90° or about 135°.

67. The plate joiner of claim 54, wherein the angle adjustment system comprises an angle locking system arranged and configured to retain the front fence at a desired angle; the angle locking system comprising a pin arranged and configured to alternatively slidably engage the first arcuate slot and the second arcuate slot and a locking nut biasing the angle segment member against the rear fence.

68. The plate joiner of claim 48, wherein:

a. the fence system further comprises a height adjustment system, and a height gauge; the height adjustment system being arranged and configured for adjusting fence height;

b. the height gauge comprises a scale and a height indicator; the scale being arranged and configured to provide a measurement of front fence height; the height indicator comprising a visible indicator with a thickness along the scale substantially equivalent to the thickness of the cutter; the height indicator being arranged and configured to indicate a front fence height on the height scale;

c. whereby by visualizing the measurement along the thickness of the visible indicator, the height gauge indicates the distance from a face of the workpiece to any point in the thickness of the cutter.

69. The plate joiner of claim 68, wherein the fence support further comprises a vertical member, and the height adjustment system further comprises the vertical member and a rear fence; the height scale is adjacent to the rear fence; and the rear fence comprises the visible indicator.

70. The plate joiner of claim 69, wherein the visible indicator comprises a raised rectangle.

71. The plate joiner of claim 69, wherein the height gauge is accurate at each selected front fence angle.

72. A plate joiner, comprising:

a. a fence support comprising a contact surface, a cutter slot defined by the contact surface, and a cutter; the cutter being arranged and configured to protrude from the fence support through the cutter slot and to make a plunge cut into a surface of a workpiece when the contact surface of the fence support is pressed against the surface and the cutter is plunged into the workpiece;

b. a drive arranged and configured to rotatably drive the cutter; and

c. a fence system comprising a front fence, and an angle adjustment system; the angle adjustment system being arranged and configured for adjusting a front fence angle;

d. the angle adjustment system comprising an angle segment member arranged and configured to position the front fence at a selected angle between a plane defined by the front fence and a plane defined by the contact surface; the angle segment member defining a first slot and a second slot, the first slot being arranged and configured to position a first range of front fence angles, the second slot being arranged and configured to position a second range of front fence angles.

73. The plate joiner of claim 72, wherein the first slot comprises an arcuate slot and the second slot comprises an arcuate slot.

74. The plate joiner of claim 73, wherein the angle segment member further comprises an angle scale comprising indicia of fence angle; and, for a given difference in fence angle, any two indicia are approximately equally separated along the scale.

75. The plate joiner of claim 74, wherein the indicia are substantially equally separated along the scale.

76. The plate joiner of claim 74, comprising approximately equally spaced indicia for each 10° difference in fence angle.

77. The plate joiner of claim 72, wherein the angle adjustment system is arranged and configured to position the front fence in the first range of angles comprising about 0° to about 90° and the second range of angles comprising about 90° to about 135°.

78. The plate joiner of claim 72, wherein the angle segment member defines a third slot arranged and configured to connect the first and second slots.

79. The plate joiner of claim 72, wherein the angle adjustment system comprises an angle indicator and the angle segment member further comprises an angle scale, the angle scale and the angle indicator being arranged and configured to indicate the first and second ranges of front fence angle.

80. The plate joiner of claim 79, wherein:

a. the angle indicator comprises a first indicator and a second indicator and the angle scale comprises a first scale and a second scale;

b. the first indicator and first scale being arranged and configured for indicating the first range of front fence angles, the second indicator and second scale being arranged and configured to indicate the second range of front fence angles;

c. the first scale and the first indicator being dissociated when the fence is positioned in the second range of fence angles.

81. The plate joiner of claim 80, wherein the second scale and second indicator are dissociated when the fence is positioned in the first range of fence angles.

82. The plate joiner of claim 72, wherein the angle adjustment system is arranged and configured to provide a positive stop at one or more front fence angles.

83. The plate joiner of claim 82, wherein the angle segment member comprises a stop member arranged and configured to stoppably contact the rear fence to provide a positive stop.

84. The plate joiner of claim 83, wherein the angle segment member and rear fence are arranged and configured to provide an adjustable stop contact. 5

85. The plate joiner of claim 84, wherein the rear fence comprises a set screw arranged and configured to stoppably contact the stop member.

86. The plate joiner of claim 85, wherein the positive stop is at a front fence angle of about 90° or about 135°. 10

87. The plate joiner of claim 82, wherein the front fence comprises a stop member arranged and configured to stoppably contact the rear fence to provide a positive stop.

88. The plate joiner of claim 87, wherein the positive stop is at a front fence angle of about 0°. 15

89. The plate joiner of claim 82, wherein the angle adjustment system is arranged and configured to provide a positive stop at a front fence angle of about 0°, about 90°, or about 135°.

90. The plate joiner of claim 72, wherein the angle adjustment system comprises an angle locking system arranged and configured to retain the front fence at a desired angle; the angle locking system comprising a pin arranged and configured to alternatively slidably engage the first arcuate slot and the second arcuate slot and a locking nut biasing the angle segment member against the rear fence. 20

91. The plate joiner of claim 72, wherein, at any selected distance from a top face of the workpiece to the fence, the distance from the top face of the workpiece to the cutter remains constant as the front fence angle is adjusted.

92. The plate joiner of claim 72, wherein the fence system is arranged and configured to provide a pivot axis substantially in a plane defined by the contact surface.

93. The plate joiner of claim 72, wherein the fence system further comprises a trunnion and a rear fence, which is substantially perpendicular to the cutter; the front fence and rear fence being pivotally coupled by the trunnion.

94. The plate joiner of claim 93, wherein the trunnion comprises an arcuate ridge member and a groove member defining an arcuate groove, the ridge member pivotally engaging the groove member; the front fence comprising the ridge member and the rear fence comprising the groove member, or the front fence comprising the groove member and the rear fence comprising the ridge member. 30

95. The plate joiner of claim 94, wherein the front fence comprises the groove member and the rear fence comprises the ridge member.

96. The plate joiner of claim 94, wherein the rear fence comprises a rear fence member and a trunnion member, the trunnion member being coupled to the rear fence member and comprising the groove member or the ridge member. 35

97. The plate joiner of claim 93, wherein the front fence and rear fence are pivotally coupled by two trunnions.

98. The plate joiner of claim 97, wherein the two trunnions are arranged and configured to provide a pivot axis substantially in a plane defined by the contact surface. 50

99. A plate joiner, comprising:

- a fence support comprising a contact surface, a cutter slot defined by the contact surface, and a cutter; the cutter being arranged and configured to protrude from the fence support through the cutter slot and to make a plunge cut into a surface of a workpiece when the contact surface of the fence support is pressed against the surface and the cutter is plunged into the workpiece;
- a drive arranged and configured to rotatably drive the cutter; and

c. a fence system comprising a front fence, a rear fence, and a trunnion; the trunnion being arranged and configured for pivoting the front fence;

d. the trunnion comprising an arcuate ridge member and a groove member defining an arcuate groove, the ridge member pivotally engaging the groove member; the front fence comprising the ridge member and the rear fence comprising the groove member, or the front fence comprising the groove member and the rear fence comprising the ridge member.

100. The plate joiner of claim 99, wherein the rear fence is substantially perpendicular to the cutter.

101. The plate joiner of claim 99, wherein the front fence comprises the groove member and the rear fence comprises the ridge member.

102. The plate joiner of claim 99, wherein the rear fence comprises a rear fence member and a trunnion member, the trunnion member being coupled to the rear fence member and comprising the groove member or the ridge member.

103. The plate joiner of claim 100, wherein the front fence and rear fence are pivotally coupled by two trunnions.

104. The plate joiner of claim 103, wherein the two trunnions are arranged and configured to provide a pivot axis substantially in a plane defined by the contact surface.

105. The plate joiner of claim 99, wherein the front fence and trunnion are arranged and configured to provide a pivot axis substantially in a plane defined by the contact surface.

106. The plate joiner of claim 99, wherein the trunnion is arranged and configured to pivot the front fence without substantial perceivable play.

107. The plate joiner of claim 99, wherein the angle adjustment system comprises an angle segment member arranged and configured to position the front fence at a selected angle between a plane defined by the front fence and a plane defined by the contact surface; and the angle segment member defines a first slot and a second slot; the first slot being arranged and configured to position a first range of front fence angles; the second slot being arranged and configured to position a second range of front fence angles. 40

108. The plate joiner of claim 107, wherein the angle segment member is pivotally coupled to the front fence and slidably engages the rear fence.

109. The plate joiner of claim 107, wherein the first slot comprises an arcuate slot and the second slot comprises an arcuate slot.

110. The plate joiner of claim 107, wherein the angle adjustment system is arranged and configured to position the front fence in the first range of angles comprising about 0° to about 90° and the second range of angles comprising about 90° to about 135°.

111. The plate joiner of claim 107, wherein the angle adjustment system defines a third slot arranged and configured to connect the first and second slots.

112. The plate joiner of claim 107, wherein the angle adjustment system is arranged and configured to provide a positive stop at one or more front fence angles.

113. The plate joiner of claim 112, wherein the angle segment member comprises a stop member arranged and configured to stoppably contact the rear fence to provide a positive stop.

114. The plate joiner of claim 113, wherein the angle segment member and rear fence are arranged and configured to provide an adjustable stop.

115. The plate joiner of claim 114, wherein the rear fence comprises a set screw arranged and configured to stoppably contact the stop member.

116. The plate joiner of claim 115, wherein the positive stop is at a front fence angle of about 90° or about 135°.

117. The plate joiner of claim 112, wherein the front fence comprises a stop member arranged and configured to stopably contact the rear fence to provide a positive stop. 5

118. The plate joiner of claim 117, wherein the positive stop is at a front fence angle of about 0°.

119. The plate joiner of claim 112, wherein the angle adjustment system is arranged and configured to provide a positive stop at a front fence angle of about 0°, about 90° or 10 about 135°.

120. The plate joiner of claim 107, wherein the angle adjustment system comprises an angle locking system arranged and configured to retain the front fence at a desired angle; the angle locking system comprising a pin arranged 15 and configured to alternatively slidably engage the first arcuate slot and the second arcuate slot and a locking nut biasing the angle segment member against the rear fence.

121. A plate joiner, comprising:

- a. a housing comprising a fence support and containing a 20 motor;
- b. the fence support containing a cutter blade rotatably driven by the motor;
- c. the fence support comprising a contact surface, which defines a cutter slot; the blade being protrudable through the cutter slot in a forward direction and retractable in a rearward direction;

d. the housing and the fence support being arranged and configured for pressing the contact surface against a joint surface, pushing the housing forward, moving the cutter forward to cut into the joint surface, and retracting the cutter into the fence support;

e. a fence assembly comprising a vertical member, a rear fence, a front fence, and an angle adjustment system; the vertical member being a portion of the fence support; the rear fence being movably mounted on a guide rod and a threaded rod, each rod being coupled to the vertical member; the rear fence being movable relative to the cutter; the front fence being pivotably coupled to the rear fence; the front fence and the angle adjustment system defining a pivot axis;

f. the pivot axis being located substantially in a plane defined by the contact surface; and

g. the front fence being pivotal between a position at a 90° angle to the rear fence and a position at a 0° angle to the rear fence, the front fence in the position at a 0° angle to the rear fence not protruding in the forward direction beyond the contact surface.

122. The plate joiner of claim 121, wherein the angle adjustment system is arranged and configured to position the front fence in a first range of angles comprising about 0° to about 90° and the second range of angles comprising about 90° to about 135°.
